UNITED STATES PATENT OFFICE.

JAMES WILLIAM WILLIAMS, OF LOUISVILLE, KENTUCKY.

HAND WASHING-RUBBER.

SPECIFICATION forming part of Letters Patent No. 329,350, dated October 27, 1885.

Application filed August 23, 1884. Serial No. 141,310. (No model.)

To all whom it may concern:

Be it known that I, JAMES WILLIAM WILLIAMS, a citizen of the United States, residing at Louisville, in the county of Jefferson and State of Kentucky, have invented new and useful Improvements in Hand Washing-Rubbers, of which the following is a specification.

My invention relates to those devices which, while being used as substitutes for the knuckles of the person in washing clothes upon the common wash-board, have also a soap-receptacle provided with a perforated bottom, the class being known in Patent Office classification as "Hand-Rubbers—Laundry."

The object of my improvement is to produce a hand washing-rubber device having a stiff rubbing perforated soap-retainer, which shall be combined with a soap receiving and covering pocket of fabric or flexible material, and wherein the hand in washing may either grasp a flange of said soap-retainer or grip the flexible pocket, whereby a rigid rubbing perforated surface practically brings the soap in direct contact with the clothes to be washed without undue waste.

The construction for carrying out this object is hereinafter fully set forth with reference to the accompanying drawings, in which—

Figure 1 represents the device in perspective, the canvas sack being grasped by a human hand; Fig. 2, a longitudinal section of the same, and Fig. 3 a cross-section.

The device is made up of a rigid rubbing-bottom, A, having corrugations *a* and holes or perforations *b*, upon which rests interiorly a cake of soap, B, so as to be brought in sufficient contact with the wetted clothes to generate lather or suds, thus practically bringing the soap in contact with the clothes. To this bottom A a soap-containing covering pocket or sack, C, open at the top, made of canvas or other suitable material, is attached by a clamp-lap, *c*, of the side rim, *d*, of the rigid bottom. The device is made to receive a standard kind of soap, and as the standard is changed in shape, so may the shape of the device be changed. The rigid rubbing-bottom may be made of wood, india-rubber, gutta-percha, or zinc, and may have any suitable kind of rubbing-corrugations, (or the corrugations may be dispensed with,) and its perfora-

tions *b* may be large or small and of any number or form. The cake of soap is placed in the sack or pocket and rests upon the rigid perforated corrugated bottom. Then the flexible sack is grasped by its mouth *D* by hand, and the device rubbed on the clothes, in place of using the knuckles of the operator. In so doing the contained soap receives enough water to make suds, and is not directly exposed to rubbing or friction over its whole surface, furnishing only so much soap as is necessary to make a required quantity of suds, for as the perforated corrugated bottom comes in contact with the wet clothes and the water in the tub the soap becomes saturated through the openings *b* in the bottom of the holder, an ample amount of suds is produced, which are immediately and thoroughly rubbed into the clothes by means of the corrugations acting upon the clothes. As the soap in the flexible sack holder diminishes in quantity another cake can be placed in the sack or pocket on top of the remnants, and so on, and thus none of the soap is unnecessarily wasted. The pocket may be used as a grasp, as shown, and the device is rubbed over the clothes as a substitute for the knuckles.

I have described the flexible sack as forming the hand-grasp for the device; but the sides of the rim *d* may be provided with hand-holds, or the rim may be turned out, so as to form grasps or flanges *c*. In either case the device forms a wash-board carried by the hand, so that the latter is not in contact with the fixed wash-board, because the hand device is rubbed on the clothes, which are placed piece by piece on the usual corrugated wash-board and in its function is auxiliary to the wash-board. In fact, this device is used precisely as the cake of soap is used in the hand on the wash-board, but with the advantage of using a rigid rubbing perforated soaping-surface upon the clothes. The perforated rubbing-bottom forms a shallow rigid pan covered with a flexible pocket, which, while serving to cover and hold the soap in the pan, may serve as the handle of the device, the two parts being secured together in any suitable way so as to leave the rubbing-surface free. In the drawings this connection is shown as being made by folding the edges of

the sack in a seam with the edges of the rim of the pan, as being a simple and effective binder for the flexible pocket.

It will be understood that whether the device is grasped and held by the side flanges of the perforated soap-retainer or by the covering flexible pocket, the hand will extend over the cake of soap and keep it pressed up to the perforated rubbing-surface as it wears away.

10 I claim—

1. The combination, in a hand-rubber for washing purposes, of a flexible pocket and a rigid perforated bottom connected to one end of said pocket, substantially as and for the 15 purpose set forth.

2. The combination, in a hand-rubber for washing purposes, of a receptacle or pocket

of flexible material, and a rigid perforated bottom having rim clamp-laps to bind and hold said bottom to said pocket, substantially 20 as and for the purpose set forth.

3. The rigid perforated rubbing-surface formed with a surrounding rim having side hand-grasps, combined with an open fabric pocket bound to the rim of said rubbing-surface, substantially as herein set forth. 25

In testimony whereof I have hereunto set my hand in the presence of two subscribing witnesses.

JAMES WILLIAM WILLIAMS.
